UNITED STATES PATENT OFFICE.

JAMES HOOGERHYDE, OF GRAND RAPIDS, MICHIGAN.

WOOD-TURNING MACHINE.

Application filed January 28, 1924. Serial No. 689,040.

To all whom it may concern:

Be it known that I, JAMES HOOGERHYDE, a citizen of the United States of America, residing at Grand Rapids, in the county of Kent and State of Michigan, have invented certain new and useful Improvements in Wood-Turning Machines; and I do hereby declare the following to be a full, clear, and exact description of the invention, such as will enable others skilled in the art to which it appertains to make and use the same.

This invention relates to a wood turning lathe by means of which a large quantity of production may be obtained of duplicate pieces. It is a primary object and purpose of the present invention to make a machine of this character wherein pieces of wood stock square in cross section may be successively brought to suitable cutters and cut to the desired form very rapidly, a single operator of the machine only being required to place the stock in place to be engaged by the machine and thereafter brought to the cutters, the operator removing the finished work and also manually operating the holder of the unfinished stock toward the cutters, the organization of the machine being such that one operator can readily perform these operations without loss of time. Further objects of the invention are to make a machine of this character which is practical and operative, and fully capable of sustaining the continuous usage to which it is subjected in practice; and to provide a machine, the controls of which are located at one end thereof, all within easy reach of a single operator while the stock may be placed in the machine and the finished product taken therefrom at the same place. Various other objects and purposes than those enumerated, together with mechanisms for attaining the same will appear as understanding of the invention is had from the following description, taken in connection with the accompanying drawings, in which,

Fig. 1 is a front elevation of the machine with parts broken away for clearer disclosure.

Fig. 2 is an end elevation thereof.

Fig. 3 is a fragmentary front elevation of one end of the pivotally mounted work holder used in the machine.

Fig. 4 is a like view of the opposite end thereof.

Fig. 5 is a fragmentary detail view partly

in section showing one of the belt driving means employed.

Fig. 6 is a fragmentary plan view of the machine.

Fig. 7 is a fragmentary enlarged side elevation and section showing the means used to limit the movement of the work holding device toward the cutters. 60

Fig. 8 is a fragmentary front elevation of the construction shown in Fig. 7, the adjusting screw being in cross section. 65

Fig. 9 is a fragmentary side elevation showing one of the holders for the square stock.

Fig. 10 is an elevation of a turned form 70 which may be made by the machine from said square stock, and

Fig. 11 is a fragmentary detail view of the means used to automatically control the driving of the work holding device. 75

Like reference characters refer to like parts in the different figures of the drawings.

In the construction, a supporting casting 1 is provided at the upper side of which two supporting brackets or heads 2 and 3 are carried, the former being divided and having two spaced apart bearings adjacent its upper portion in which a shaft 4 is rotatably mounted. The bracket 3 carries a spindle 5 similar to a tail stock spindle in wood turning lathes, while the shaft 4 is similar to a head stock spindle. Between the ends of the shaft 4 and spindle 5 a bar 6 is located which is adapted to carry any desired collection of cutters for the production of a desired form in turning wood. When shaft 4 is driven, the bar 6 with the cutters thereon rotates at a high degree of speed. An electric motor 7 has its shaft in alignment 80 with the shaft 4 and the adjacent ends of the shafts are connected by means of any suitable coupling, indicated at 8. The motor is supported on a bracket 9 attached to one end of the main supporting casting 1. 85

On the shaft 4 near the coupling 8 a pulley 10 is located around which a belt 11 passes, said belt also passing around a wheel 12 mounted on a short shaft 13 which is mounted in any suitable manner at one end 90 of and back of the support 1. A pulley 14 is fixed on shaft 13 and drives a belt 15 which in turn passes around and drives a wheel 16 mounted on a shaft 17 which extends across in front of the support 1, being 105 110

2
mounted in suitable brackets 17^a projecting in front of the support 1. When the belt passes around the drive pulley 14 and thence directly to the wheel 16, said wheel is driven 5 in one direction. To drive the wheel in the opposite direction, upper and lower arms 18 extend from the bracket supporting the shaft 13 and carry idlers 19 which serve to mount the belt as shown in Fig. 5, that is 10 the belt passes around in front of the drive pulley 14 and thence upwardly and downwardly around and back of the idlers 19.

The shaft 17 serves as a support for the pivotal mounting of a work holding device.

15 In construction said device comprises a rigid frame having a plurality of vertical spaced apart legs 20, the lower ends of which are pivotally mounted on the shaft 17. These legs are integrally connected by cross members a distance above their lower ends and by a table member 21 at their upper ends, the upper surface of which is flat and positioned substantially horizontal. A head stock 22 is permanently secured at one end 20 of the table (see Fig. 3) and like the part 2 heretofore described has two spaced apart upwardly extending arms, each formed with a bearing at its upper end. A short shaft or spindle 23, like a wood turning 30 lathe head stock spindle is rotatably mounted in the bearing at the upper end of the inner of said arms and a shaft 24 is mounted in the other bearing in alinement with spindle 23. A clutch 25 is used to connect the 35 said shaft 24 and spindle 23. Normally the clutch is separated and the shaft and spindle are not connected. A sprocket wheel 26 is fixed to the outer end of shaft 24 and is driven by a chain 27 which passes around a second sprocket wheel 28 rotatable with the wheel 16.

40 The tail stock 29 (see Fig. 4) is fixed at the opposite end of the table 21 and at its upper end has a sleeve through which a tail stock spindle 30 passes, being mounted for longitudinal movements. Spindle 30 is provided with a rack 31 at its upper side at one end with which a pinion 32 fixed on a short shaft or pin 33 engages, the pin 33 being 45 mounted for rocking movements and having a weighted handle 34 extending therefrom for manual operation of the same. The wood that is to be turned is square in cross section, preferably, and is shown at 35 as a square stick of a length to be received between the head and tail stock spindles, the weighted arm 34 normally moving the spindle 30 so that it engages an end of the part 35 and presses the opposite end into engagement with the head stock spindle.

Links 36 at one end are pivotally connected to the legs 20 of the pivotally mounted frame and at their rear ends are pivotally connected to arms 37 which are secured on a rock shaft 38 rotatably mounted in suit-

able bearings formed in two forwardly extending brackets 39 which are permanently attached to the main support 1. An operating lever 38^a is secured to the end of the rock shaft nearest the tail stock end of the 70 table 21 and the same may be manually operated. When turned toward the machine as shown in full lines in Fig. 2, the pivotally mounted frame and the mechanism carried thereon are moved toward the machine; and when turned back, the pivotally mounted frame is moved away to occupy the position substantially shown in dotted lines in Fig. 2.

75 When the frame carrying the work holding head and tail stocks is moved toward the support 1, the clutch at 25 is automatically connected. To accomplish this, a bar 40 having a cam shaped edge 40^a (see Fig. 7) is secured to and projects forwardly from the 80 main support 1. A lever 41 is pivotally mounted between its ends at 42 on the pivotally mounted work carrying frame (see Fig. 85 3), and its upper end is formed as a yoke 43 to engage with the collar 25^a on one member of the clutch 25, the lower end being 90 equipped with a small roller 44. As the pivotally mounted frame moves toward the support 1, roller 44 rides against the cam edge 40^a of the bar 40 and operates the lever 41 automatically to bring the clutch members 95 into operative engagement for the driving of the spindle 23, as is evident.

100 It is necessary to limit the movement of the work carrying member toward the main support and the cutters. This is done by means of an adjusting and stop screw 45 threaded through a depending flange to the table 21, as shown in Fig. 7, and locking the screw in any position to which it is adjusted by a lock nut 46, preferably of the form shown. The outer end of screw 45 is provided with an operating head 45^a for manual operation. The end of the screw coming 105 against the main support 1 stops the movement of the work toward the cutters at a predetermined position so that the cutters on the bar 6 can act on the work 35 only to a certain point, thus determining the size of the finished article.

110 In front of the rock shaft 38 a rod 47 is located and supported by the brackets 39. Members 48 are adjustably clamped on the rod 47 and each carries a vertical rod 49. On each rod 49 a fixture 50 is adjustably clamped, and each of said fixtures carries a rod 51 located horizontally and likewise adjustably clamped in said fixtures. The rods 51 extend toward the machine and on each 115 a member 52 is adjustably mounted and formed with an upwardly projecting leg 52^a, the two parts 52 and 52^a providing a seat with sides located at right angles to each other so as to receive the bar 35 square in cross section. These holders for the stock 120 125 130

bars 35 are located so that when the work holding device is moved back and away from the cutter mechanism, the ends of the head stock and tail stock spindles 23 and 30 5 are positioned so as to properly engage the ends of the said bars 35, as shown in the dotted lines in Fig. 2 and also as indicated in Fig. 6.

In the operation of the machine, the motor 7 is running continuously, driving the bar 6 and the cutters thereon at high speed. The spindle or shaft 24 is driven continuously but at a much reduced speed. Supposing the pivotally mounted frame to be in the 15 dotted line position shown in Fig. 2, and a bar 35 seated in the holders therefor, the tail stock spindle 30 is moved so that it engages the adjacent end of the bar and presses the opposite end of the bar into secure engagement with the spindle 23. Handle 38^a 20 is then grasped and thrown to the full line position shown in Fig. 2, thus rocking the shaft 38 and moving the pivotally mounted frame about the axis of the shaft 17, bringing the bar 35 to the cutters on the rapidly 25 rotating bar 6. Simultaneously with this movement, the roller 44 on the lever 41 rides on the cam edge 40^a of the bar 40 and operates the clutch 25 so that the tail stock spindle 30 is rotated slowly, thereby turning the bar 35 with a comparatively slow motion. By the time the bar 35 has been turned through one complete revolution, the finished article turned to form is completed. In Fig. 30 35^a, at 35^a, a finished shape is shown, one of the many forms that may be made with different varieties of cutters on the bar 6. Handle 38^a is then brought back to its first position and the pivotally mounted frame moved to dotted line position, the weighted arm 34 operated to release the turned article 35^a which is removed, a new bar 35 placed in the holders therefor and the operation repeated. In practice, the handle 38^a 40 45 will be moved from its full line position shown in Fig. 2 to the dotted line position and during this movement, the finished article 35^a released and removed, a bar 35 having been placed in the holders therefor while 50 the turning operation is being performed so that as soon as the pivotally mounted frame reaches the outer position, the lever or handle 34 may be operated to engage the new bar. This makes for great rapidity of production.

The various adjustments of the limit stop to the pivotally mounted frame, of the fixtures 50 on the rods 49, of the rods 51 on said fixtures, and of the holders of the stock bars 60 on the rods 51 make it possible to use the machine with different sizes of stock with respect to cross sectional dimensions, and by adjusting the tail stock 29 to different positions and properly adjusting the members 65 48, different lengths of stock may be used.

Of course, the cutter assembly on the bar 6 may be any combination desired for the production of a required form, and is subject to wide variation. If at any time it is desired to turn the bar 35 in a direction opposite 70 from what it has been rotated, this can be done through the belt guide mechanism shown in Fig. 5. This may be desirable under certain conditions, and means is provided therefor. 75

The machine is very practical and in practice has proved its merits as a quantity production machine in turning wood to desired round forms. The invention is defined in the appended claims and is to be considered 80 as comprehensive of all forms of structure coming within the scope of said claims.

I claim:

1. In a machine of the class described, a main support, a bar on which a cutter assembly may be mounted positioned horizontally and mounted for rotation at the upper side of the support, a motor for driving said bar at high speed, a frame located in front of the support and pivotally mounted thereon at its lower end to move toward or away from the support, means for manually moving said frame, head and tail stocks attached at the upper side of the frame, a longitudinally movable spindle mounted horizontally 90 through the tail stock spindle, a shaft and a head stock spindle located in alinement and rotatably mounted in the head stock, a normally disconnected clutch between said shaft and spindle, a lever pivotally mounted 95 between its ends on the frame and connected with the clutch, a cam member carried by the support over which the lever rides at one end to operate the clutch to connecting position when the frame is moved inward toward the support, means for driving the said shaft from the motor at a low rate of speed, and fixed means in which a length of material may be placed so as to lie between and aline with the said head and tail stock 100 spindles when the frame is moved outward away from the frame. 105

2. In a machine of the class described, a support, a bar mounted above the support for rotation on which a cutter assembly is adapted to be secured, a motor for driving the bar at high speed, a substantially vertical frame located in front of the support and pivotally mounted thereon at its lower end for turning toward or away from the support, brackets attached to and extending forwardly from the support, a rock shaft mounted in said brackets, arms attached to the rock shaft, links connecting the arms to the frame, a handle attached to one end of the rock shaft for manual operation thereof, head and tail stocks carried at the upper side of the frame in spaced apart relation, a tail stock spindle mounted for longitudinal movement in the tail stock, means for 115 120 125 130

manually moving said spindle, a shaft and a head stock spindle rotatably mounted in the head stock in alinement with each other, a normally disconnected clutch interposed between the said shaft and spindle, means for continuously driving the shaft from the motor at low speed, a lever pivotally mounted between its ends on the frame and having one end engaged with the clutch, a bar attached to and projecting from the support having a cam edge against which the other end of the lever bears on movement of the frame inwardly toward the support to thereby connect the clutch, and means for limiting the inward movement of the frame toward the support.

3. A construction containing the elements in combination defined in claim 2, combined with a rod carried by said brackets, vertical rods located in spaced apart relation carried by said first rod and extending upwardly therefrom, a horizontal rod carried by each vertical rod and extending inwardly toward the support, and members mounted on said horizontal rods, each having a right angular seat for the seating of a length of material square in cross section, said members being located so that the length of material lies between the head and tail stock spindles when the frame is at its outer position away from the support.

4. In a machine of the class described, an elongated vertical support, a shaft and a spindle mounted on said support above the upper side thereof and located in horizontal alinement, a bar located between the shaft and spindle on which cutters are adapted to be assembled, said bar rotating with the shaft, a motor connected with and driving the shaft, a second shaft mounted horizontally in front and adjacent the lower end of the support, a wheel mounted for rotation on the second shaft, a second wheel mounted back of the first wheel, means for driving the second wheel from the motor, a drive pulley of relatively small diameter connected with the second wheel, means for

driving the first wheel from said pulley, a frame positioned substantially vertical in front of the support and mounted on the second shaft at its lower end for movement toward or away from the support, head and tail stocks carried at the upper side of the frame, a longitudinally movable spindle mounted in the tail stock, means for manually moving said spindle, a third shaft and a second spindle mounted for rotation in the headstock and positioned in alinement, a normally disconnected clutch interposed between the head stock spindle and third shaft, means to drive the third shaft from the first wheel, brackets extending forwardly from the support, a rock shaft mounted horizontally therethrough, arms attached to the rock shaft, links connecting the arms to the frame, a handle attached to one end of the rock shaft for manually turning the same, a lever pivotally mounted between its ends on the frame and having its upper end connected with the clutch, a bar attached to the support and projecting forwardly therefrom, said bar at one edge having a cam form against and over which the opposite end of the lever rides to connect the clutch when the frame is moved toward the support, means for limiting the inward movement of the frame, a rod positioned horizontally between and carried by the outer ends of the brackets, members mounted on said rod, a vertical upwardly extending rod connected with each member, a horizontal rod connected to each of the vertical rods adjacent its upper end and extending inwardly and a device mounted on each rod formed with a seat to receive a length of material rectangular in cross section, said devices being located so that the length of material held therein is located between and in alinement with the head and tail stock spindles when the frame is moved to outer position.

In testimony whereof I affix my signature.

JAMES HOOGERHYDE
